UNITED STATES PATENT OFFICE.

JOSEPH MARIE ETIENNE FRANC, OF ANDANCETTE, FRANCE.

AIR-PUMP FOR INFLATING PNEUMATIC TIRES.

1,350,926.

Specification of Letters Patent. Patented Aug. 24, 1920.

Application filed August 22, 1919. Serial No. 319,273.

To all whom it may concern:

Be it known that I, JOSEPH MARIE ETIENNE FRANC, a citizen of the French Republic, and resident of Andancette, Department of the Drôme, in the Republic of France, have invented certain new and useful Improvements in Air-Pumps for Inflating Pneumatic Tires, of which the following is a specification.

10 This invention relates to improvements in air pumps for inflating pneumatic tires and it has for its object to provide an improved pump having one or more cylinders operated by motor and distinguished by the use 15 of cams, the application of controlling springs for the return of the pistons and the system of engagement and disengagement of the apparatus.

In the accompanying drawings with reference to which the invention is described an air pump is shown having three cylinders. In these drawings:—

20 Figure 1 shows a section of same along the line A—A of Fig. 2, and

25 Fig. 2 is a longitudinal sectional elevation showing the cam-shaft, cylinders, pistons, etc., the valve system being shown on one cylinder only.

As shown the apparatus consists of three 30 cylinders *a* cast solid or in parts. In the said cylinders the pistons *b* move provided with packing rings *c*. The pistons *b* are operated, when ascending in the cylinders by cams *d* and when descending they are 35 actuated by spiral springs such as *e* of a truncated cone shape, the large end bearing on the upper inside or cover of the cylinders, while the small one rests on the top of the pistons *b*.

40 The cams *d* are keyed on to their shaft *d'* so as to equalize the pressure thereon. The shaft *d'* carrying said cams *d* rests on the bearings *f* which form part of the frame of the machine which frame forms at *g* an oil 45 chamber in which the cams plunge. The result of this immersion is that the whole apparatus is lubricated by the oil projected by centrifugal force.

In the upper part of the cylinders are 50 screwed on covers *h* which carry the valves and their springs. The whole arrangement is inclosed by a cap *i* which covers all the heads of the cylinders *a* and is formed at *j* with the air outlet passage. Such passage 55 may also if desired be arranged at the top

of the cap, or else at the sides. Two small columns *k* hold the cap firmly in its place.

The shaft *d'* which carries the cams *d* is hollow. Another shaft *l* which carries on one side the spur wheel *n*, is capable of sliding longitudinally in its interior. The said shaft is made either square or round with engaging studs which key the two shafts together against relative rotation and give the driving connection.

As the pump is not to be constantly in gear with the motor, a system of engagement and disengagement is provided by moving the inner shaft *l* which permits the above working. As represented in Fig. 2 70 the gear wheel *n* engages the motor gear wheel and its helicoidal teeth such as *o* are arranged in such manner that the thrust which always accompanies this kind of cog is always produced in the direction of the 75 apparatus and so that under the influence of such thrust, the gear wheel *n* therefore always tends to bear against the end *p* of the outer cam shaft *d'* which shaft is provided at *q* with a collar provided for manual movement of such shaft where disconnection of the gears is desired.

Hence, while the pump is working, no 80 artificial maintenance of gear connection is necessary considering that it is the thrust 85 of the helicoidal teeth which stabilizes the starting gear.

For the disengagement, all that is necessary is to displace the gear wheel *n* by pushing back the inner shaft *l* by means of the collar *m*. During this performance, the sliding inner shaft *l* effects the disengagement of the gear wheels and then the pump is at once stopped.

Circumferential apertures *r* (Fig. 1) are 90 provided around each cylinder for the admission of air into the cylinders, except in those parts where they are in contact.

In order to facilitate the guiding of the piston and to avoid wear, the cam shaft is 100 out of center relatively to the center of the pistons and the cylinder.

An oil hole not shown in the drawing, is provided for filling up the oil case *g*.

For the purpose of reducing the weight, 105 the pistons may be hollow and the cams may be provided with holes therethrough and for cooling purposes ribs may be provided at the top of the cylinders and on the back.

What I claim is:—

65

70

75

80

85

90

95

100

110

1. An air pump for inflating pneumatic tires comprising a casing, a plurality of cylinders thereon, valves in said cylinders, pistons slidably mounted therein, a cam shaft, cams on said shaft in operative engagement with the pistons, the said cams being in equal angular relation on the shaft according to the number of cylinders, and spiral springs bearing on the tops of the pistons
10 for keeping them up to the working faces of the cams on the return strokes of the pump, the cam shaft being made hollow and having slidably mounted therein another shaft, a spur wheel secured on such inner shaft and formed to be held in engagement with a coöperating pinion through its tooth formation, whereby the inner shaft may be moved to disengage such spur wheel at will.
2. An air pump for inflating pneumatic tires, comprising a plurality of cylinders 20 opening into a bottom casing, spring-pressed pistons mounted in the cylinders, a hollow cam shaft mounted in the casing and having a cam for each piston, a cover for each cylinder having a valve controlling the 25 outlet for such cylinder, a cover for all said valves forming an air chamber for all cylinders, and driving means mounted in and longitudinally operable relative to such hollow shaft.

30
In testimony whereof I have hereunto signed my name.

JOSEPH MARIE ETIENNE FRANC.
